UNITED STATES PATENT OFFICE

1,941,044

PROCESS OF CROSSWISE WRAPPING OF
GOODS

Johannes Neff, Dresden, Germany, assignor to
"Universelle" Cigarettenmaschinen-Fabrik, J.
C. Mulier & Company, Dresden, Germany

Application April 15, 1931, Serial No. 530,421; and
in Germany April 23, 1930

8 Claims. (Cl. 93—2)

The applicant has previously proposed to wrap goods, for instance a plurality of groups of cigarettes arranged one above the other, by means of two wrapping strips that cross one another at right angles, and to place the goods thus wrapped directly into the packing box. In this operation the ends of the first strip rest on the upper side of the goods, either overlapping one another or just meeting, or leaving a free space between them. It has now been discovered that these strip ends—when wrapping the ends of the second strip which are positioned on the same side of the packet—can easily become disarranged, producing an incomplete, unsightly package which has to be considered as waste. The first strip must have the same width as the whole package, so that therefore its outer edges are particularly liable to damage.

Now this invention consists in that after the folding of the first strip, the strip-ends on the upper side of the packet are kept in position, by means of compressed air during the folding of the ends of the other strip on the same upper side of the packet and are secured.

25 The compressed air is preferably directed only on to one or more points of the folded ends of the first strip. Moreover, the compressed air is passed through the ram which co-operates in the folding of the second strip.

30 One form of construction of the invention is illustrated in the annexed drawing, in which:—

Fig. 1 is a front elevation.

Fig. 2 is a side elevation, and

Fig. 3 shows a special construction.

35 After the group 'G' of cigarettes has been wrapped in the manner shown in Fig. 3 with the first wrapping strip E, which is generally of "parchment" paper, so that the flaps L' and L² of the wrapping strip, either overlap or, as in the case of the present example, have a gap left between them, this package is thrust in front of a shaping channel or the like on one side of which a ram 1 is arranged and on the other side the packing box Sch resting on the flexibly arranged ram 1'.

40 Now a second wrapping strip E' at right angles to the wrapping strip E is placed between the channel and the packing box Sch, so that when the ram 1 descends into the position indicated, the group of cigarettes is thrust into the packing box Sch, and at the same time the two flaps L³ and L⁴ are bent upward in the manner shown in Fig. 2.

Now in order that, on the return of the ram 1 into the position indicated by dotted lines, the flaps L' and L² of the first wrapping strip should

not be bent up, i. e. should remain on the cigarette-groups, the ram 1 is provided with an air chamber 3 which is connected with a passage 4' in the ram-shaft 4. Nozzle passages 5 lead from the air chamber 3 to the lower surface of the ram 1. To the end 4" of the ram-shaft 4 an air tube is attached through which compressed air is passed to the ram. Now if the ram 1 rises compressed air leaves from the nozzle passages 5 and places the flaps L' and L² of the wrapping strip E on the group of cigarettes, while by known means such as a folding finger 6 or the like, the flaps L³ and L⁴ of the wrapping strip are placed around and on the package.

The compressed air valve may be controlled in such manner that on the introduction of the packing member shown in Fig. 3, the flow of compressed air is cut off and only when the ram 1 is raised is the valve opened so that the compressed air can emerge from the nozzle passages 5.

It should be noted that the filled boxes are deposited in a conveying channel 7 in the direction indicated by an arrow in Fig. 2.

Having thus described the nature of the said invention and the best means I know of carrying the same into practical effect, I claim:—

1. A process of wrapping articles comprising folding a strip of material about said articles and then folding a second strip of material about said articles while retaining said first strip in position by means of compressed air.

2. A process of wrapping articles comprising folding a strip of material about said articles, maintaining the ends of said strip substantially in fixed position by means of compressed fluid and then folding a second strip of material about said articles while the ends of said first strip are held in position by said compressed fluid.

3. A process of wrapping articles comprising folding a strip of material about said articles, then directing a stream of compressed fluid at a point upon each end of said strip to maintain said strip in position about said articles and then folding a second strip of material about said articles while the ends of said first strip are maintained in position by said compressed fluid.

4. A process of wrapping articles comprising folding a strip of material about said articles, then directing streams of compressed fluid against the ends of said strip to maintain said strip in substantially fixed position about said articles and then folding a second strip of material about said articles transversely to said first strip while the ends of said first strip are maintained in position about said articles.

5. A process of wrapping articles comprising folding a strip of material about said articles, then placing a strip of material at right angles to said first strip under said articles, and then forcing said articles with said strips into a carton while maintaining the ends of said first strip in substantially fixed position by means of compressed air to thereby fold upwardly about the ends of said articles said second strip and then folding the ends of said second strip about said article while the ends of said first strip are still maintained in fixed position about said articles.

10 6. A process of wrapping articles comprising folding a strip of material about said articles, placing another strip of material transversely of said first strip underneath said articles, then forcing said articles with said strips into a container by means of a reciprocating ram, then raising

said ram while directing a stream of compressed air through said ram against the ends of said first strip to maintain said first strip in position and then folding the ends of said second strip over the ends of said first strip while the ends of said first strip are maintained in position by said compressed air.

15 7. A process of wrapping articles in a plurality of strips of material which includes the step of maintaining one strip in position by means of compressed air while the other strips are folded into position.

8. A process of wrapping articles in two strips of material which includes the step of maintaining the ends of the first strip in position by means of compressed fluid while the second strip is folded about said articles.
